UNITED STATES PATENT OFFICE.

CHARLES FORTH, OF DETROIT, MICHIGAN, ASSIGNOR TO CAPITAL MANUFACTURING CO., OF DETROIT, MICHIGAN, A CORPORATION OF MICHIGAN.

EXHAUST GAS HEATER.

Application filed September 10, 1923. Serial No. 661,896.

This invention relates to exhaust heaters for motor cars. The object of the invention is to provide an improved heater of this type provided with passageways for adequate circulation around the pipes. The grid or slotted foot plate is so designed that when it rests on the heating coils it divides the heater into two passageways, one which takes in the air and the other delivers the heated air. This affords air circulation which is absolutely necessary to get effective heating operation. As is well known in the operation of furnaces in houses, without free and adequate circulation of a large quantity of air the furnace will not properly heat the house, and the same is true in heating the interior of a car.

Most of the radiators that are used in the cars at the present time have no adequate provision for securing proper circulation of the air. The consequence is that under ordinary city running speed very little heat is derived from them. Consequently, they are very ineffective. It is the object of the present invention to overcome this fault and secure an effective circulation by a simple arrangement.

The heaters that are now used in automobiles are provided with dust pans for collecting dust and trash and also provided with doors by which this may be dropped out of the pan. However, so far as I am aware, these doors have no means by which they can be controlled from above the floor of the car. I have not only provided a control, but one which is sunk in the grid when not in use or not to be in the way.

In the drawings:

Fig. 1 is a fragmentary perspective view 40 of the interior of a sedan.

Fig. 2 is a longitudinal section of my improved heater taken on the line 2—2 of Fig. 1.

Fig. 3 is a cross section of the same taken 45 on the line 3—3 of Fig. 2.

Fig. 4 is a plan view of the heating pipes.

Fig. 5 is an inverted plan view of the heater showing the pan doors taken on the line 5—5 of Fig. 2.

50 The grid is a casting designated *a* and provided with the usual parallel bars and slots, but of course, the exact design and

pattern of the grid is immaterial. However, a large portion of the grid is raised up from the floor flange *b*. This has a 55 double purpose. One is to form a convenient foot rest for the occupants of the seat and the other is for the purpose of affording an adequate intake passage all around the outside of the grid. Openings *c* are provided for taking in air. All around the grid is a depending flange *d* adapted to rest on the top of the copper heating element so as to divide the space below the top of the grid 60 into an intake chamber and a heated-air 65 delivery chamber.

The heating element or pipes are formed by a pair of sheet copper stampings *e* and *f*, which are lock-seamed together. These stampings of course, are relatively cheap to 70 manufacture and being made of copper or any other suitable metal, the heat conductivity is relatively large. The lower stamping is formed with a pair of nipple portions *h*—*h* adapted to fit over the nipple inserts *g* 75 by being brazed to the shoulder formed by the expanded ring *j*. This expanded ring portion provides a second or lower shoulder which is adapted to rest on the shoulder *k* provided in the stamped metal pan. This 80 shoulder *k* is provided around the orifices through which the nipple inserts are intended to pass. The lower portion of the nipple inserts are externally screw threaded to take the elbows *m* which can be screwed 85 onto these threads and which at their other ends can take the flexible pipe or hose intended to convey the exhaust gases. It will be noted that the stamped metal pan is provided with upper outwardly turned 90 flanges *n* adapted to rest below the flanges *b* of the grid on the floor of the car. The screws or bolts *o* can pass on through both flanges and this securely holds the pan and grid together and also secures them to the 95 floor of the car, thereby suspending the pan below the grid.

The bottom of the pan is provided with a pair of door openings, guarded by the spring closed doors *p*. These doors each have a pair 100 of knuckle eyes *q*. The bottom of the pan also has two pairs of knuckle eyes *r*; the pintles are threaded through these knuckle eyes and the torsion springs *t* are coiled around the

spindles and tend to keep the doors tightly closed. It is not broadly new to provide doors in the bottom of the pan and keep them tightly closed by springs, but I do believe that my control is a new and better arrangement for operating these doors than has heretofore been suggested. The grid is provided with an integral downwardly projecting sleeve *u*, adapted to take the spindle *v* on the end of which is pinned a double crank *w*. This spindle may be shifted up and down in the sleeve *u*. The position shown in Fig. 3 is the lower position with the crank handle *x* sunk below the level of the top surface of the grid in the socket *y*. This keeps the crank handle out of the way yet in a position where it may be easily grasped for operation. When it is desired to dump the contents of the pan, the handle is grasped and the spindle may be raised due to the fact that the crank is somewhat spaced from the lower end of the spindle and the fact that it has flexible connections in the wire links *z* which connect with the lugs *1*, soldered to the doors. When the crank is turned in either direction, it obviously pulls in on both the links *z* and thrusts the doors open, allowing the refuse to be dumped.

The feature that I want to emphasize in particular is the simple circulatory arrangement of the grid provided with the depending flange which rests upon the top of the heating element. This requires the air to be taken in at the sides of the heating element where it can be taken in for the reason that the rising heat does not stop the down draft of air. The air flows down all around the outside of the heating element and down under the heating element, rising in the center of the heating element through the slots *2*. After having become thoroughly heated by its being trapped for some time under the bottom of the heater it will flow through the grid, being retarded by the web portions of the web. This forms a simple circulation which is both adequate and efficient.

What I claim is:

1. In an exhaust heater, the combination of a grid and a pan forming a housing, an exhaust gas heating element comprising a plurality of separated pipes united by a header, said heating element supported in the pan, and a depending flange depending from the bottom of the grid and resting on the heating element to divide the interior of the housing into an air intake chamber along the margin of the grid and a heated air delivering chamber on the inside of the grid.
2. An exhaust heater comprising a pan and a grid which form a housing, an exhaust gas heating element within the housing having an inlet and an outlet for the passage of exhaust gases therethrough, the said exhaust

gas heating element being disposed in the housing so as to provide a space between the element and the grid, and partition means for dividing the space into an air intake chamber and an air exhaust chamber.

3. In an exhaust heater, the combination of a grid, a pan depending from the grid and provided with a refuse door normally spring closed, a spindle supported in the grid and having connections with the refuse door, and a handle on top of the spindle by which the spindle may be operated to control the refuse door.

4. In an exhaust heater, the combination of a grid provided with a depending sleeve portion, a pan supported under the grid and provided with a refuse door, and a spindle supported in the sleeve having a crank on its lower end and a crank handle on its upper end, the lower crank having a link connection with the refuse door whereby a turning of the spindle controls the refuse door.

5. In an exhaust heater, the combination of a housing, provided with a refuse door, said housing provided with a grid having a countersunk socket at the top and with a sleeve, a spindle operating in said sleeve and having a crank handle which may be sunk out of the way into said countersunk socket, and connections between the lower end of the spindle and the door by which the same may be controlled.

6. In an exhaust heater, the combination of a housing provided at its upper surface with a grid having a countersunk socket and having a refuse door at the bottom, and a spindle rotatably and slidably supported in said grid and having at its lower end connections with the refuse door and having on its upper end a crank handle which may lie in the countersunk socket when not in use but which permits the handle of the spindle to be drawn from out of the socket and turned to operate the refuse door.

7. In an exhaust heater, the combination of a grid provided with a countersunk socket in its upper surface, a pan supported so as to be suspended below the grid and provided with a pair of refuse doors, a longitudinally movable and rotatable spindle supported on the grid, and a double crank on the lower end of the spindle linked to both refuse doors, whereby a turning of the spindle will control the refuse doors.

8. In an exhaust heater, the combination of a grid, a stamped metal pan provided with an opening in the bottom and a nipple insert having an expanded ring portion for resting on the shoulder formed around the opening, a heating element having a nipple portion adapted to rest on the top of the ring portion and secured thereto, and a pipe fitting adapted to be secured to the lower end of the nipple insert.

9. An exhaust heater comprising, a pan

and a grid which form a housing, and an exhaust gas heating element supported within the housing, this element consisting of spaced pipes which are connected at their ends by 5 headers to form an unbroken boundary for the heater, and means on the grid for engaging with this unbroken boundary of the heater, said means being disposed inwardly of the outer edge of the grid whereby the housing is divided into an outer air intake 10 chamber and an inner air exhaust chamber.

In testimony whereof he has affixed his signature.

CHARLES FORTH.
